STAPLE DRIVING MECHANISM

Walter Henry Holley, St. Mary Cray, Kent, England, assignor to McGarry and Cole Limited, London, England, a British company

Application February 5, 1958, Serial No. 713,500

Claims priority, application Great Britain
February 18, 1957

1 Claim. (Cl. 1-49)

The present invention relates to a staple-driving mechanism. In most staple-driving mechanisms the staple travels only a short distance down a guideway from the staple magazine before coming into contact with the work to which the staple is to be applied.

In some constructions of stapling mechanisms, however, it is necessary that the magazine should be remote from the point at which the staples are applied to the work, because the staple magazine projects laterally from the staple driver and guideway. A particular example of a construction of this kind is a staple rammer which may be used, for example, in the manufacture of bedding, for the stapling of coil springs to a bed base in furniture manufacture. In such an application it is necessary to be able to insert the stapling head through the springs, and to allow this to be done the laterally projecting magazine has to be at a height sufficient to clear the top of the springs when the staple head is in contact with the work.

It will be appreciated that in such a construction the staple driver blade has a long travel, since it must be capable of being raised sufficiently in its guideway to pick off the leading staple from the pack of staples in the magazine.

With this type of staple driving mechanism it is very easy to get two staples in the staple guideway at the same time by raising the driver blade past the magazine without the preceding staple having been expelled from the guideway. As a consequence, the mechanism is frequently jammed unless special steps are taken to prevent this.

It is the principal object of the present invention to provide a staple-driving mechanism with a means for preventing a further staple being picked from the staple magazine until the preceding staple has been expelled from the guideway.

In accordance with the present invention a staple-driving mechanism is provided with a catch mechanism located within the body of the stapling head of the mechanism to prevent the staple driver blade being raised to a height sufficient to permit the entry of a staple from the magazine into the staple guideway, unless the blade has been moved down the guideway substantially to its bottom end. This is achieved by providing a catch member carried by the staple driver and a sliding sleeve movable through a limited distance lengthwise of the staple driver and over the catch member, the sleeve rendering the catch member inoperative at the upper position of the sleeve and releasing the catch member at its lower position, the sleeve being movable between two stops in the body located so as to cause the sleeve to move up the stapled driver as the driver reaches the bottom end of its travel and to move down the staple driver as it reaches the top end of its travel. There is also provided a catch-engaging stop adapted to engage the catch member during upward movement of the driver with the sleeve in its lower position so as to arrest the driver before the blade

2

uncovers the magazine. The catch-engaging stop may be and preferably is co-incident with the upper stop for the sleeve.

One construction of staple-driving rammer made in accordance with the present invention is hereinafter described with reference to the accompanying drawings, wherein:

Figure 1 is a side view of a staple-driving rammer of a type for which a catch mechanism of the present invention is suitable.

Figure 2 is a longitudinal section of the rammer of Figure 1.

Figure 3 is a diagrammatic cut-away perspective of the catch mechanism on a larger scale.

Figures 4 to 7 are sectional side views of the staple driving rammer of Fig. 1 which illustrate the operation of the catch mechanism.

The staple rammer shown in Figures 1 and 2 of the drawings is generally of well-known construction and only the novel catch mechanism associated with it will be described in detail. The stapling head of the rammer has, in a conventional manner, a barrel 1 made up of a channel member having a block member between the arms of the channel member at its lower end, so as to define a narrow guideway of just sufficient size to permit the passage of a staple and of the staple-driving blade 2.

A staple magazine 3 of conventional construction projects laterally from the side of the barrel to feed staples individually from a pack of staples into the guideway in a conventional manner.

The staple barrel 1 of the stapling head of the rammer is provided with a rubber grip 4. The staple-driving blade 2 is driven by a staple driver having a weighted handle 5 and a shank 6 guided in the barrel 1, the blade 2 being held in driving connection with the shank 6. In ordinary operation the handle 5 is pulled out until the bottom end of the blade 2 has cleared the staple magazine and reaches the position shown in Figure 4, to permit another staple to be fed into the guideway from the magazine. The blade 2 is then drivable to the position shown in Figure 7 in which the bottom end of the blade just reaches the bottom end of the barrel 1 and further travel of the handle is prevented by contact between the handle and the top end of the barrel.

The construction and operation of the rammer up to this point is conventional.

The top end of the driver rod 6 is a round portion 7 and guided in a round hole in an end cover member 8 secured to the top end of the barrel 1.

The top end of the barrel 1 has a square section guideway for a portion 9 of the staple driver, upon which staple driver the staple driver blade 2 is carried. The portion 9 is of generally square section for movement in this portion of the barrel, but one corner of the square portion of the driver is cut away to permit it to pass a bottom end stop 10 in the form of a triangular piece of metal let into one corner of the guideway. The stop 10 and the portion 9 of the driver could, of course, take other co-operating shapes.

The catch mechanism, which forms the special feature of the present invention, is mounted on the round portion 7 of the driver 6. The catch mechanism consists of a bow-shaped catch member 11 having a rounded rear surface 12 to permit the member 11 to rock on a flat surface 14 on the portion 7, and a square section sleeve 15 adapted to slide in the square section portion of the barrel 1.

The operative part of the catch member is the end face 16 and the upper end of the catch member is therefore spring-loaded by means of a small compression spring 17 bearing against a ball 18, positioned in a cross drilling

in the portion 7. (The spring 17 and ball 18 are shown exploded in Figure 3 for clarity.)

When the sleeve 15 is at its bottom position, the bottom end of the catch member 11 is trapped within the sleeve and the upper end of the catch projects above the surface of the rod, so that the end face 16 is raised to its operative position.

If the driver 6 is thrust all the way down, as required for driving a staple, the sleeve 15 hits the bottom end stop 10 and slides up the round portion 7. In so doing, the bow-shaped catch member 11 is rocked on its rounded back surface and moved into an inoperative position in which the end face 16 is within the periphery of the portion 7 and does not project above its surface.

The top end cover 8 houses a hardened collar 19 which likewise has a round aperture through it in which the round portion of the shank is guided. The collar 19 acts as the upper stop for the square section sleeve 15, which slides down the round portion 7 when arrested by this upper stop, until the sleeve comes down firmly against the shoulder provided by the top of the portion 9 of the driver. The collar 19 thus also prevents the driver from being drawn up out of the barrel.

When the sleeve 15 is in its upper position, the end face 16 of the catch member 11, as it lies within the periphery of the portion 7, is able to enter the hole in the collar 19, as shown in Figure 4.

On the other hand, when the end face 16 of the catch member 11 is in its operative position, it hits the end surface of the collar 19 and the staple driver 6 is arrested against further upward movement before the blade 2 has been raised sufficiently to uncover the end of the staple magazine 3 for the feed of the next staple.

In order to expose a larger surface on the end of the collar 19 for the catch member 11 to engage, a shallow inclined slot 20 (Figure 7) is preferably cut in the top end of the barrel wall, into which the upper end of the catch member 11 enters, so that it is pressed outwardly by its spring 17 to project out of the rod farther than it otherwise would.

In this case the catch-engaging stop and the upper

sleeve stop are co-incident (both being the collar 19), but it will be appreciated that by minor modification, other similar and operative arrangements are possible.

It will be appreciated that as the staple driver reaches the top of its travel (Figure 4), the sleeve 15 is pushed down the round portion 7 of the staple driver to release the catch member 11, the top end of which is then free to move outwardly under the force of the spring 17 when it is withdrawn from the hole in the collar 19. If the driver is, for instance, only moved as far as the position shown in Figure 5 and then again withdrawn, the upward movement of the driver will be arrested as shown in Figure 6, and it will be impossible to raise the blade 2 sufficiently to pick another staple from the magazine 3 until the catch member is again rendered inoperative by driving the blade 2 to the position shown in Figure 7.

I claim:

In a staple-driving mechanism of the type in which staples are fed consecutively from a magazine into a staple guideway in the body of the mechanism when the blade of a staple driver is raised sufficiently to clear the magazine, a catch mechanism for preventing the introduction of a further staple into the staple guideway, the said catch mechanism comprising a catch member carried by the staple driver and a sliding sleeve movable through a limited distance lengthwise of the staple driver and over the catch member, the sleeve rendering the catch member inoperative at the upper position of the sleeve and releasing the catch member at its lower position, upper and lower stops being positioned in the body to co-operate with said sleeve, the lower stop being positioned to engage the sleeve and move it lengthwise up the driver and over the catch as the driver reaches the bottom of its travel and the upper stop being positioned to engage the sleeve and move it lengthwise down the driver to uncover the operative upper end of the catch member as the driver reaches the top of its travel and to engage the catch member on upward movement of the driver with the sleeve in its lower position so as to arrest the driver before the blade uncovers the magazine.
